UNITED STATES PATENT OFFICE

THOMAS HENRY JONES, OF WOODTHORPE, ENGLAND

METHOD OF PRODUCING STOCKINGS AND SOCKS

Application filed March 28, 1930, Serial No. 439,739, and in Great Britain March 28, 1929.

This invention relates to stockings and socks and has for one of its objects to provide an improved method of manufacturing same, which method is particularly advantageous 5 when producing stockings or socks having patterned legs and foot uppers and plain sole.

Broadly the invention consists in forming on a circular knitting machine a stocking 10 in one continuous piece comprising a leg portion of tubular fabric, a flat selvedged extension constituting the foot upper, a pocket shaped toe portion, a second flat selvedged part constituting the foot sole and a second 15 pocket forming the heel.

By making a stocking as above it will be appreciated that the leg and foot upper can be patterned as desired, while the sole which is formed as an integral part of the whole, 20 is maintained plain.

Another important object of the invention is to enable a greater range or variation of patterns or pattern effects to be produced by change-over or reverse plating in stockings 25 and socks made on a circular knitting machine. Heretofore in order to obtain a plain sole the plated pattern continued on to the foot upper from the leg has of necessity been confined to not more than two colours, the 30 reason for this being that when the foot upper and sole are simultaneously knitted as a tubular part and one of the threads employed in the pattern of the upper provides the colour of the sole, any thread or threads 35 retained out of knitting position will float across the sole; this being also the case where entirely separate yarn is introduced for knitting the sole.

Another feature of the invention therefore 40 resides in providing a stocking or sock having a foot upper in more than two colours produced by change-over or reverse plating, a plain (one-colour) sole, no transverse floating threads across the foot, and said sole constituting an integral part of the stocking.

For the purpose of more fully describing the nature of this invention reference will now be made to the accompanying drawing, wherein:

Figure 1 illustrates in an extended form

the knitted piece which when seamed up constitutes the stocking.

Figure 2 shows the stocking as it appears when taken from the machine and prior to seaming.

Figure 3 shows the completed foot portion.

In one method of carrying out the invention a plain or ribbed top or welt of a stocking or sock is first produced and subsequently on the same or a separate machine a tubular leg portion 1 is knitted. On completion of the leg, the rotary motion of the machine is discontinued and reciprocation commenced on approximately half of the needles to produce a flat selvedged portion 2 constituting the instep or foot upper the remaining needles being moved up out of operation and still retaining their stitches, and when a sufficient length of said flat is knitted a pocket or bag-like piece 3 is produced constituting 70 the toe.

From this toe is knitted by continued reciprocation a further flat selvedged extension 4 which is to form the foot sole, said sole 4 terminating in a second pocket portion 5 75 constituting the heel.

After knitting the pocket heel 5 the displaced needles with stitches thereon may be brought down and full rotary motion of the machine is advantageously proceeded with to 80 produce a few full circular courses 6 on all needles, (Figure 2), thus knitting the heel to the lower end of the leg at each ankle, after which the fabric is removed from the machine.

In this way an article is knitted comprising a tubular leg from the one half of which at its lower end extends a flat part with two pocket portions, the extension being folded back on itself at the toe pocket, and preferably being definitely joined at the ankles by knitting the aforesaid limited number of full circular courses all as shown in Figure 2. After removal of the articles so formed from the machine, the two side openings 7 in the 95 foot are seamed up or linked, the final half-circular course at the top of the heel being also linked or seamed up to the final half-circular course at the rear of the leg to provide a joint extending from ankle to ankle 100

across the rear of the stocking above the heel. The final full courses 6 constitute ravelling courses which may be produced from cheaper yarn and facilitate the linking process, such courses rendering unnecessary the careful handling of the stocking after removal from the machine and before the linking.

If desired, however, these ravelling courses may be omitted, in which case the article may be cast off from the machine after knitting the pocket heel, the cast off edge of said heel being subsequently seamed up to the half-circular lower edge of the leg. 10 It will be seen that in a stocking according to this invention no seam or joint occurs across the toe.

A stocking as above can be produced by reverse plating, and as the sole is knitted at 20 a different time from the upper, it will be understood that two or more colours can be incorporated in the leg and foot upper while providing a plain sole without loose floating threads. For instance, during the knitting 25 of the tubular leg and selvedged upper, two pairs of pivotally displaceable thread feeders may be employed, said pairs being brought into use alternatively or selectively at predetermined intervals, and when the 30 sole is being knitted entirely different yarn can be employed or any one of the threads used in the patterned leg and upper may be caused to appear continuously on the face of said sole. In this latter case a splicing yarn 35 may also be introduced during the production of the sole.

When a different yarn is employed for the sole, the change-over plating guides are automatically bluffed at the commencement of 40 the pocket toe, and one additional guide brought into use.

The toe and heel pocket portions are produced by displacing needles upwardly with 45 stitches thereon at each side edge of the flat piece so as gradually to narrow said piece until only a small number of needles are in action and then gradually bringing said displaced needles down again until the full 50 width is reached, thus forming two oppositely tapering pieces which are joined together at their tapering edges.

It is to be understood that the size of the 55 foot may be reduced by moving more than one half of the machine needles into an upper or inoperative position during the knitting thereof.

I claim:—

1. The method of producing a stocking or 60 sock on a circular knitting machine which consists in first knitting by rotary motion a tubular leg portion, then moving approximately one half of the circular row of needles to an inoperative position with the previously 65 formed stitch loops retained thereon and proceeding by reciprocation to knit on the

remaining needles a selvedged foot upper portion, a pocket toe, a selvedged foot sole and a pocket heel, subsequently returning the said inoperative needles to the operative position and producing by rotary motion a 70 number of full circular ravelling courses, and finally after removal of the garment from the machine seaming together the foot upper and sole along the foot sides and the rear lower end of the leg to the heel. 75

2. The method of producing a stocking or 80 sock on a circular knitting machine which consists in first knitting by rotary motion a tubular leg portion, then moving a number less than one half of the total number of 85 needles in the circular row to an inoperative position with the previously formed stitch loops retained thereon and proceeding by reciprocation to knit on the remaining needles a selvedged foot upper portion, a pocket toe, a selvedged foot sole and a pocket heel, 90 the said foot upper and sole being of smaller diameter than the tubular leg portion, subsequently returning the said inoperative needles to the operative position and producing by rotary motion a number of full circular 95 ravelling courses, and finally after removal of the garment from the machine seaming together the foot upper and sole along the foot sides and the rear lower end of the leg to the heel. 100
